(57) CLAIM

The ornamental design for a portion of a shoe, as shown and described.

DESCRIPTION

FIG. 1 is a lateral side view of a portion of a shoe showing my new design;

FIG. 2 is a rear view thereof;

FIG. 3 is a medial side view thereof;

FIG. 4 is a medial-side rear perspective view thereof; and,
FIG. 5 is a lateral-side rear perspective view thereof.

The uneven broken lines immediately adjacent to the shaded area on the medial and lateral sides represent unclaimed portion of the boundary of the design. The uneven broken line showing of the remainder of the shoe forms no part of the claimed design.
